UNITED STATES PATENT OFFICE.

JOHN CLARK, OF BUFFALO, NEW YORK

HOISTING HOOK.

Application filed September 15, 1925. Serial No. 56,431.

To all whom it may concern:

Be it known that I, JOHN CLARK, citizen of the United States, residing at Buffalo, in the county of Erie and State of New York, have invented new and useful Improvements in Hoisting Hooks, of which the following is a specification.

This invention relates to a hoisting hook for use in connection with various kinds of hoisting tackle and has for its object the production of a hoisting hook of this character which can be quickly applied to and removed from a load and which will remain reliably connected with the load and not become fouled with other objects.

In the accompanying drawings:—

Figure 1, is a vertical longitudinal section of a hoisting hook embodying my invention.

20 Figure 2, is a horizontal section of the same taken on line 2-2, Fig. 1.

Figure 3, is a front elevation of the hoisting hook.

Figure 4, is a horizontal section taken on line 4-4, Fig. 3.

Figure 5, is a fragmentary vertical section taken on line 5-5, Fig. 1, showing the clamping screw nut locked against backward rotation.

20 Figure 6, is a similar view showing the clamping screw nut unlocked and free to unscrew.

Figure 7, is a perspective view of the locking pin.

35 Figure 8, is a fragmentary vertical section taken on line 8-8, Fig. 1.

Similar characters of reference indicate like parts throughout the several views.

The main part or body of this hoisting hook comprises an upright shank 10 and a

forwardly and upwardly turned back 11 at the lower end of this shank forming an upwardly opening mouth between the two

wardly opening mouth between this shank and beak which is adapted to receive the ring, wire or other means whereby the lead

ring, rope or other means whereby the load to be lifted is attached to the hoisting hook. At its upper end the shank is provided with

At its upper end the shank is provided with means whereby the same is connected to the hoisting mechanism. In the present in-

hanging mechanism. In the present instance this is accomplished by means of an eye 12 which overhangs forwardly from the

12 which overhangs inwardly from the upper end of the shank and receives the lowermost link 13 of a hoisting chain forming part of the hoisting tackle or mechan-

ism, such as that now in common use for 55 this purpose.

Movable into and out of a position across the mouth of the hoisting hook is a keeper or latch 14 which is preferably permanently connected with the upper part of the shank while its lower end is detachably connected with the beak of the hoisting hook so as to permit of opening and closing the mouth of the same.

At its lower end this keeper or latch is provided with an inwardly projecting hook 15 which in its operative position projects inwardly through an opening 16 in the upper part of the beak.

At its upper end the keeper is provided with an upwardly projecting foot 17, the inner side of which is adapted to bear against the opposing upper part of the inner side of the shank 10. The upper part of the inner side of this foot is rounded, as shown at 18 and adapted to engage with the adjacent rounded surface 19 on the upper part of the inner side of the shank 10 and thereby permit the keeper to be locked or turned in a vertical plane parallel with the beak 11 and shank 10 for the purpose of engaging and disengaging the hook 15 of the keeper with the opening 16. The foot of the keeper is provided with a vertical slot 20 which receives the central part

tical slot 20 which receives the central part of a clamping or tightening bolt 21 which latter is connected at its inner end with the adjacent upper part of the shank 10 by means of a screw joint 22, as shown in Figs. 1 and 2. The outer end of the bolt 21 is provided with a screw thread 23, preferably of the acme type which receives a clamping screw nut 24 adapted to engage with the outer side of the foot 17 of the keeper and press the same against the shank 10 for the purpose of holding the keeper across the mouth of the hoisting hook and in an interlocked position with the beak of the same. In order to permit the keeper to rock freely in a vertical plane parallel with the shank 10 and beak 11 upon loosening the clamping bolt 24 only to a moderate extent the co-operating surfaces of the clamping nut 24 and the coupling foot 17 of the keeper are constructed so that a spherical joint or ball joint is formed between the same, this being accomplished by making the inner side 25 of the nut of convex spherical

form and the outer side of the foot 17 of concave spherical form, as shown in Figs. 1 and 2.

Complete detachment of the clamping nut 24 from the clamping and pivot bolt 21 is prevented by means of a stop device which preferably consists of a stop disk 27 arranged on the outer end of the clamping bolt 21 and over-hanging the sides of the same and detachably connected with this bolt by means of a screw 28 or other suitable means. In order to avoid making the clamping bolt 21 unduly long and still permit the clamping nut 24 to be unscrewed as far as necessary to completely release the keeper a recess 29 is formed on the outer side of this nut which receives the stop disk 27 in the outermost position of this nut.

Turning of the clamping nut 24 may be effected in any suitable manner for instance by providing the periphery thereof with teeth 30 shown in Fig. 1, and also by inserting a wrench pin into one or another of a plurality of wrench openings 31 formed in different parts of the periphery of this screw nut, as shown in Figs. 1 and 2.

When this hoisting hook is in use and the keeper is locked in a position across the mouth of the same the hook 15 of the keeper engages with the opening 16 of the beak 11, the foot 17 of the keeper engages the lower end of its slot 20 with the clamping bolt 21 and the screw nut 24 presses this foot against the upper part of the shank 10, as shown by full lines in Fig. 1. For the purpose of opening the mouth of the hook in order to permit the load to be detached from the mouth thereof and another load substituted, the screw nut 24 is first loosened by unscrewing the same sufficiently for this purpose after which the keeper may be turned in a vertical plane parallel with the plane of the shank 10 and beak 11, at which time the foot 17 at the upper end of the keeper will slide downwardly between the nut and shank 10 until the upper part of the slot 20 of the foot engages with the top of the clamping bolt 21, thereby releasing the hook 15 of the keeper from the beak 11, as shown by dotted lines 14^a in Fig. 1. The keeper may now be swung in a vertical plane at right angles to the plane of the shank and beak of the hoisting hook for the purpose of completely uncovering the mouth of the hoisting hook, this extreme opening position of the keeper being represented by dotted lines 14^b in Fig. 1.

Upon reversing the operation of the parts as just described the keeper will be again returned to its working position for closing the mouth of the hoisting hook and confining the load therein.

In order to produce a positive upward pull of the shank on the keeper in addition

to the frictional pull against the same by means of the clamping bolt and nut an upwardly facing shoulder 32 is formed on the central part of the inner side of the shank 10 which shoulder engages with the adjacent upper part of the surface of the keeper, as shown in Fig. 1.

In order to positively interlock the stub bolt 21 with the shank of the hoisting hook and prevent this bolt from unscrewing or shifting its position circumferentially upon tightening or loosening the clamping screw nut 24 a locking or retaining device is provided which in the preferred form shown in the drawings is constructed as follows:—

The numeral 50 represents a key face preferably of flat form arranged on the lower side of the bolt 21 and formed thereon by cutting away a portion of the peripheral surface of this bolt adjacent to the front side of the shank of the hook. Immediately below this bolt and adjacent to the key face 50 the front side of the shank and the hook is provided with a recess 51 which registers with the key seat of the bolt 21. In this key recess is arranged a locking key 52 which is preferably secured therein by means of a driving fit and which engages its upper flat side with the key face 52 on the bolt 21, as shown in Figs. 1 and 8.

By this means an obstruction is provided in the path of rotation of the clamping bolt 21 which positively prevents the latter from being turned and thereby insures against loosening or unscrewing of this bolt when unscrewing the clamping nut 24, thereby reliably holding the several parts of the hoisting hook in their properly assembled position so that the same is always in condition for use and thus insures maximum safety to the operators while the hook is employed as part of a hoisting tackle for lifting or transporting the load from one place to another.

In order to prevent the clamping screw nut 24 from being accidentally unscrewed or loosened and render the attachment of the hook to the load unreliable means are provided whereby this clamping screw nut after being tightened on the bolt 21 and against the foot of the keeper will be locked against turning backwardly, the locking means for this purpose being manually controlled so that the clamping screw nut may be locked or unlocked at will. In the preferred form of this locking device the same utilizes the teeth 30 on the periphery of the clamping screw nut as a part of these means, and in the preferred organization in which these teeth are thus used each tooth is provided with an inclined front side and an inclined rear side so that in effect the several teeth on the clamping screw nut form an annular ratchet rim. Each of these teeth is adapted to be engaged by a locking pawl

53 which is mounted on the keeper and adapted to be moved into and out of the path of the ratchet teeth so that when this pawl engages with one of the ratchet teeth, 5 as shown in Fig. 5, the screw nut 24 will be held against turning backwardly, while upon disengaging this pawl from the respective ratchet teeth, as shown in Fig. 6, the path of the ratchet rim will be clear 10 and the clamping screw nut can be turned freely either forwardly or backwardly on the bolt 21. In the preferred construction this locking pawl is formed on the periphery of a locking pin 54 which is rotatably 15 mounted in a recess 59 on the front side of the keeper immediately below the screw nut 24 when the keeper is in its operative position. The locking pin 54 is preferably connected with the keeper by means of an external screw thread 55 on the inner or rear 20 end thereof engaging with the corresponding screw thread at the inner end of the recess 59, whereby this screw joint not only serves as a means for permitting the 25 locking pin to rotate for engaging and disengaging the pawl 53 with the ratchet rim of the nut 24 but it also serves as the means for connecting this locking pin with the keeper in a manner which is durable and 30 reliable in operation. The turning of this locking pin for moving the locking pawl 53 into and out of engagement with the ratchet rim of the screw nut may be effected in various ways, for instance by applying 35 a wrench to a prismatic head or enlargement 56 at the front end of the locking pin 54 or this same result may be obtained by a tightening rod or pawl inserted in one or the other of a plurality of pin openings 57 40 formed in the facets of the head 56 of the locking pin. In the preferred construction the head 56 overhangs the front face of the clamping screw 24 when the parts are in their operative position, but if at any 45 time it is desired or necessary to move the clamping screw nut 24 and the locking pin 54 independently of each other, this can be done by turning the keeper into its 50 uppermost position and also sliding the same lengthwise upwardly into the position indicated by dotted lines 14^b in Fig. 1, whereby the screw nut and locking pin 55 clear each other sufficiently to avoid interference and permit them to be readily assembled and dismembered relative to the 55 other parts of the hoisting hook.

In order to prevent the head 56 of the locking pin 54 from becoming caught 60 against an obstruction while raising the hoisting hook or when lowering anything else close to this hoisting hook the upper side of this head 56 is bevelled or rounded as shown at 58 in Figs. 1, 2, 4 and 7, thereby causing anything which engages this particular part of the locking pin to glance 65 off and be deflected laterally therefrom, thereby preventing any interference with the free movement of the hook and also avoid fouling of the same with any hoisting tackle. In the preferred construction this bevelled surface is preferably arranged in rear of the center of this bolt when the latter is in its locked position, as shown in Figs. 3 and 4, thereby causing any engagement 70 of an obstruction with the front upper part of this hook to further tighten or move the same in the direction for locking the clamping screw instead of exerting a tendency which would loosen the same.

By means of this locking device for the clamping screw nut the latter is positively locked in its tightened position and prevented from loosening or turning backwardly so that the keeper is reliably held in its locked position in engagement with the beak 75 of the hoisting hook and all danger of the hoisting hook becoming detached from the load which it is carrying is avoided, thereby furnishing the maximum safety for the operators who are using this hook as a part 80 of a hoisting tackle.

It will be noted that in this hoisting hook no springs or similar resilient means are employed which are liable to become weak or inoperative in time and thus impair the 85 efficiency of the hook, instead all of the devices in this hoisting hook are very rigid and of sturdy character which are capable of withstanding rough usage without liability of becoming deranged or rendered inoperative.

I claim as my invention:—

1. A hoisting hook having a shank and a beak, a clamping bolt arranged on the front side of said shank, a keeper movable into and out of a position across the mouth of said hook and pivotally mounted at its upper end on said bolt and adapted to engage and disengage its lower end with said beak, a screw nut working on the thread of said bolt, and locking means for preventing said screw nut from turning backwardly.
2. A hoisting hook having a shank and a beak, a clamping bolt arranged on the front side of said shank, a keeper movable into and out of a position across the mouth of said hook and pivotally mounted at its upper end on said bolt and adapted to engage and disengage its lower end with said beak, a screw nut working on the thread of said bolt, locking means for preventing said screw nut from turning backwardly consisting of an annular row of teeth arranged on the periphery of the screw nut, and a locking member movably mounted on the shank and adapted to be engaged and disengaged with the teeth of said screw nut.
3. A hoisting hook having a shank and

a beak, a clamping bolt arranged on the front side of said shank, a keeper movable into and out of a position across the mouth of said hook and pivotally mounted at its upper end on said bolt and adapted to engage and disengage its lower end with said beak, a screw nut working on the thread of said bolt, locking means for preventing said screw nut from turning backwardly consisting of an annular row of ratchet teeth arranged on the periphery of said screw nut, and a locking pin pivotally mounted on said shank and provided on its periphery with a pawl adapted to be moved into and out of engagement with a ratchet tooth of said nut.

4. A hoisting hook having a shank and a beak, a clamping bolt arranged on the front side of said shank, a keeper movable into and out of a position across the mouth of said hook and pivotally mounted at its upper end on said bolt and adapted to engage and disengage its lower end with said beak, a screw nut working on the thread of said bolt, locking means for preventing said screw nut from turning backwardly consisting of an annular row of ratchet teeth arranged on the periphery of said screw nut, and a locking pin pivotally mounted on said shank and provided on its periphery with a pawl adapted to be moved into and out of engagement with a ratchet tooth of said nut, said locking pin being provided at its inner end with an external screw thread and said shank being provided with a threaded opening which receives the threaded part of said pin.

5. A hoisting hook having a shank and a beak, a clamping bolt arranged on the front side of said shank, a keeper movable into and out of a position across the mouth of said hook and pivotally mounted at its upper end on said bolt and adapted to engage and disengage its lower end with said beak, a screw nut working on the thread of said bolt, locking means for preventing said screw nut from turning backwardly, consisting of an annular row of ratchet teeth arranged on the periphery of said screw nut, and a locking pin pivotally mounted on said shank and provided on its periphery with a pawl adapted to be moved into and out of engagement with a ratchet tooth of said nut, said locking pin being provided at its inner end with an external screw thread and said shank being provided with a threaded

opening which receives the threaded part of said pin and the outer end of said pin being provided with a head.

6. A hoisting hook having a shank and a beak, a clamping bolt arranged on the front side of said shank, a keeper movable into and out of a position across the mouth of said hook and pivotally mounted at its upper end on said bolt and adapted to engage and disengage its lower end with said beak, a screw nut working on the thread of said bolt, and locking means for preventing said screw nut from turning backwardly consisting of an annular row of ratchet teeth arranged on the periphery of said screw nut, and a locking pin pivotally mounted on said shank and provided on its periphery with a pawl adapted to be moved into and out of engagement with a ratchet tooth of said nut, said locking pin being provided at its inner end with an external screw thread and said shank being provided with a threaded opening which receives the threaded part of said pin, and the outer end of said pin being provided with a head, the upper side of which is rounded.

7. A hoisting hook having a shank and a beak, a clamping bolt arranged on the front side of said shank, a keeper movable into and out of a position across the mouth of said hook and pivotally mounted at its upper end on said bolt and adapted to engage and disengage its lower end with said beak, a screw nut working on the thread of said bolt, locking means for preventing said screw nut from turning backwardly and means for preventing said bolt from turning on said shank consisting of a key arranged on the shank and engaging with the side of the bolt.

8. A hoisting hook having a shank and a beak, a clamping bolt arranged on the front side of said shank, a keeper movable into and out of a position across the mouth of said hook and pivotally mounted at its upper end on said bolt and adapted to engage and disengage its lower end with said beak, a screw nut working on the thread of said bolt, locking means for preventing said screw nut from turning backwardly, said bolt being provided on its periphery with a key face and said shank being provided on its front side opposite said key face with a key recess, and a locking key arranged in said recess and engaging with said face.

JOHN CLARK.
